DESIGN FOR A FINGER RING

Tibor M. Pajzs, Shorewood, Wis.

Application April 14, 1939, Serial No. 84,281

Term of patent 3½ years

To all whom it may concern:

Be it known, that I, Tibor M. Pajzs, a citizen of the Kingdom of Hungary, residing at Shorewood, in the county of Milwaukee and State of Wisconsin, have invented a new, original, and ornamental Design for a Finger Ring, of which the following is a specification, reference being had to the accompanying drawing, forming part thereof.

In the drawing:

Fig. 1 is a side view of the finger ring showing the new design with hands unclasped;

Fig. 2 is a top view of the finger ring with the hands unclasped;

Fig. 3 is an opposite side view of the finger ring with the hands unclasped; and

Fig. 4 is a top view of the same finger ring with the hands clasped.

I claim:

The ornamental design for a finger ring, as shown.

TIBOR M. PAJZS.
